UNITED STATES PATENT OFFICE.

FRANK H. LAMB, OF HOQUIAM, WASHINGTON.

WIRE-STRETCHER.

No. 851,529.

Specification of Letters Patent.

Patented April 28, 1907.

Application filed December 18, 1906. Serial No. 348,466.

To all whom it may concern:

Be it known that I, FRANK H. LAMB, a citizen of the United States, residing at Hoquiam, in the county of Chehalis, State of Washington, have invented certain new and useful Improvements in Wire-Stretchers, of which the following is a specification, reference being had therein to the accompanying drawing.

This invention relates to a wire stretcher, and particularly to a structure in which the jaws are adapted to alternately grip the wire so as to simulate a hand over hand pull without any travel of the stretching mechanism. The invention has for an object to provide a plurality of alternately operated gripping jaws connected with a single operating lever so that when one jaw is in engagement and pulling relation with the wire to be stretched, the other jaw is advancing to a position for a subsequent pull in the reversal of the operating lever. By this means a stretching action is secured in which the direction of movement of the operating lever may be reversed and the range of action is not limited to the length of the bar or other supporting device so that the stretching or pulling can be continued as long as desired.

Other and further objects and advantages of the invention will be hereinafter set forth and the novel features thereof defined by the appended claims.

In the drawing:—Figure 1 is a side elevation; Fig. 2 is a top plan with the handle in section; Fig. 3 is a vertical section on the line 3—3, Fig. 1.

Like numerals of reference indicate like parts in the several views of the drawings.

The numeral 1 designates a supporting bar of any desired configuration which is preferably provided at one end with an attaching device 2 by which it may be held against longitudinal movement. This bar is provided with the depending bracket 3 upon the lower end of which the operating lever 4 is pivotally mounted at 5, while at the opposite sides of its fulcrum this lever has attached thereto connecting links 6 and 7 by means of the pivots 8, as shown in Fig. 1. These links are each pivotally connected at 9 to the lower ends of the gripping levers 10, said levers being mounted upon the jaw blocks 11 which are slidably mounted upon the bar in any desired manner. This may be accomplished by means of the open sided recess or channel 12 within the block into which the bar 1 is

adapted to fit and to be retained in position by means of the gripping lever 10 held against the opposite faces of the bar by its pivoting bolt 13 mounted in the block. The upper end of this lever carries any desired form of gripping device 14, for instance, having a curved face which engages or bites against the wire in one movement of the lever and slips on the wire in the opposite movement thereof. The operating lever is provided with any desired form of handle 15, while at the end of the bar 1 is a suitable guide 16 through which the wire passes, and the outer face of the block 11 is provided with the rib 17 to retain the wire against lateral displacement thereon. The links 6 and 7 may each be provided with recesses 18 upon their faces to permit the operating lever to be thrown into a horizontal position for transportation or other purposes, while each of these links is provided at its point of connection with the gripping lever with a spring 19 which maintains it in a forward position in contact with the wire.

In the application of the stretcher the attaching end 2 is secured to any support, such as a pole, post or other relatively fixed member by means of the usual chain or connection and in the operation thereof, if the lever 4 is thrown toward the left, in Fig. 1, the blocks and gripping devices will be forced apart, one being in gripping contact with the wire while the other slips thereon. In the opposite movement of the lever to the right these gripping devices are drawn toward each other with one in contact with the wire and the other slipping thereon so that an alternating gripping action is secured and the stretching occurs in both the forward and backward strokes of the handle by an action similar to a hand over hand pulling upon the wire or cable to be stretched.

It will be seen that this stretcher is not limited in its length of action to the length of its support and is capable of pulling any desired length of wire which may be continued as long as necessary. The gripping jaws may be adapted in configuration to any special work or material to be stretched so as to prevent injury thereof while securing the most efficient grip for the stretching action.

The invention embodies such simplicity of construction as to obviate any danger of derangement of the parts thus providing for the most accurate and efficient operation.

Having now described my invention and

set forth its merits, what I claim and desire to secure by Letters Patent is:—

1. In a wire stretcher, a bar, an operating lever pivotally mounted thereon, a gripping device slidably mounted on said bar, a gripping lever carried by said device, and a connecting link between the operating and gripping lever to oscillate the latter in the reciprocation of said device.
  2. In a wire stretcher, a bar, an operating lever pivotally mounted thereon, a gripping device slidably mounted on said bar, a gripping lever carried by said device, a connecting link between the gripping and operating levers, and a tension spring connecting the gripping lever and link.
  3. In a wire stretcher, a bar, an operating lever pivotally mounted thereon, gripping blocks slidably mounted on said bar, a gripping lever carried by each of said blocks, a connecting link between each of the gripping levers and the operating lever, and an upper gripping jaw carried by the free end of each gripping lever.
  4. In a wire stretcher, a supporting bar, an operating lever pivotally mounted thereon, a gripping block slidably mounted upon said bar and having a recessed face to receive the same, a gripping lever pivotally mounted upon the recessed face of said block to retain the bar therein, and a connecting link from said gripping lever to the operating lever.
  5. In a wire stretcher, a supporting bar
- provided with a depending bracket, an operating lever pivotally mounted upon said bracket, gripping devices slidably mounted upon the bar at opposite sides of said lever, and connections from the lever to the gripping devices for moving the same toward and from the lever.
6. In a wire stretcher, a supporting bar provided with a depending bracket, an operating lever pivotally mounted upon said bracket, gripping devices slidably mounted upon the bar at opposite sides of the lever, connections from the lever to the gripping devices for moving the same toward and from the lever, a guide at one end of said bar, and an attaching device carried by the opposite end thereof.
7. In a wire stretcher, a supporting bar, an operating lever pivotally mounted thereon, gripping devices slidably mounted upon said bar and provided with levers, and links extending from one end of said levers and pivoted to the operating lever at the opposite side of the fulcrum thereof, said links being provided with recessed faces to seat at opposite sides of the fulcrum of the lever.
- In testimony whereof, I affix my signature in presence of two witnesses.

FRANK H. LAMB.
